(57) **CLAIM**

The ornamental design for an antenna, as shown and described.

DESCRIPTION

FIG. 1 is a top plan view of an antenna, showing a new design; and,
FIG. 2 is a top plan view of a second embodiment of the new design.

All claimed surfaces of the design are flat, coplanar, and in fixed positions relative to each other.
Only the black areas are claimed.

1 Claim, 2 Drawing Sheets

FIG. 1

FIG. 2
